195,190

PREFORMED NECKTIE

Belle A. Kandarian, 920 R St., Fresno, Calif.

Filed Oct. 8, 1962, Ser. No. 72,026

Term of patent 14 years

(Cl. D3—16)

FIG. 1 is a front elevation of a preformed necktie showing my new design.

FIG. 2 is a side elevation of the preformed necktie.

FIG. 3 is a rear elevation of the preformed necktie.

FIG. 4 is a top plan view thereof.

I claim:

The ornamental design for a preformed necktie, as shown.

References Cited in the file of this patent

UNITED STATES PATENTS

D. 75,607	Bixler	June 26, 1928
D. 161,269	Karp	Dec. 19, 1950
1,949,851	Alper	Mar. 6, 1934

OTHER REFERENCES

Sports Apparel, November 1945, p. 46, "Sport ties with doggie design from Signet."